[57] CLAIM

The ornamental design for a contoured insole, as shown and described.

DESCRIPTION

FIG. 1 is a top front perspective view of a contoured insole showing our new design for use on the right foot;

FIG. 2 is a bottom rear perspective view thereof;

FIG. 3 is a front end view thereof;

FIG. 4 is a rear end view thereof;

FIG. 5 is a right side view thereof;

FIG. 6 is a left side view thereof;

FIG. 7 is a bottom plan view thereof;

FIG. 8 is a top plan view thereof; and,

FIG. 9 is a top plan view of a contoured insole showing a second embodiment of our new design for use on the left foot, the other view all being mirror images of those of the first embodiment.
